UNITED STATES PATENT OFFICE

116,956

DESIGN FOR A FLASHLIGHT CASE

Arthur Katzinger, Glencoe, Ill.

Application February 20, 1939, Serial No. 83,113

Term of patent 14 years

To all whom it may concern:

Be it known that I, Arthur Katzinger, a citizen of the United States, residing at Glencoe, in the county of Cook and State of Illinois, have invented a new, original, and ornamental Design for a Flashlight Case, of which the following is a specification, reference being had to the accompanying drawing, forming a part thereof.

Fig. 1 is a side view of a flashlight case, embodying my new design.

Fig. 2 is a front end view thereof.

Fig. 3 is a rear end view thereof.

I claim:

The ornamental design for a flashlight case, substantially as shown.

ARTHUR KATZINGER.

CERTIFICATE OF CORRECTION.

Design No. 116,956.

October 3, 1939.

ARTHUR KATZINGER.

It is hereby certified that the above numbered Design patent was erroneously issued to the inventor, said "KATZINGER" whereas said patent should have been issued to The Edward Katzinger Company, of Chicago, Illinois, a corporation of Illinois, as assignee of the entire interest therein, as shown by the record of assignments in this office; in the heading to the printed specification, line 4, for "Serial No. 83,113" read Serial No. 83,112; in the drawing, Figures 1, 2 and 3 should appear as shown below instead of as shown in the patent - and that the said Letters Patent should be read with this correction therein that the same may conform to the record of the case in the Patent Office.

Signed and sealed this 26th day of December, A. D. 1939.

(Seal)

Henry Van Arsdale,
Acting Commissioner of Patents.
